(57) **CLAIM**

The ornamental design for a children's tricycle, as shown and described.

DESCRIPTION

FIG. 1. is a front elevational view of a children's tricycle showing my new design;

FIG. 2. is a rear elevational view thereof;

FIG. 3. is a left side elevational view thereof;

FIG. 4. is a right side elevational view thereof;

FIG. 5. is a top plan view thereof;

FIG. 6. is a bottom plan view thereof; and,

FIG. 7. is a perspective view thereof.

The cross hatching, which is partially shown, is understood to repeat uniformly across the surfaces where it is shown.
